UNITED STATES PATENT OFFICE.

HALFDAN NORBOM, OF BLOOMFIELD, NEW JERSEY.

VALVE.

1,173,731.

Specification of Letters Patent. Patented Feb. 29, 1916.

Application filed April 17, 1915. Serial No. 21,955.

To all whom it may concern:

Be it known that I, HALFDAN NORBOM, a citizen of the United States, residing at Bloomfield, in the county of Essex and State 5 of New Jersey, have invented certain new and useful Improvements in Valves; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 This invention has reference, generally, to improvements in valves; and, the present invention relates, more particularly, to a novel valve for use with steam, water, air or gases, which is of such construction that 20 under normal conditions, that is when the valve is closed, the outlet of the valve-casing is completely shut-off from the inlet of the valve-casing, or from the pressure in the inlet-side of the valve, but when partially 25 operated, the outlet-side is slightly opened to the inlet-side of the valve, so as to gradually equalize the pressure, and when finally and completely operated, a full opening- 30 relation of the outlet-side of the valve is had with the inlet-side of the valve.

The present invention, therefore, has for its principal object to provide a novel and simply constructed, as well as an effectively operating valve of the general character 35 hereinafter set forth and for the purposes herein above stated.

Other objects of the present invention not at this time more particularly enumerated will be clearly understood from the 40 following detailed description of the said invention.

With the various objects of the present invention in view, the invention consists, primarily, in the novel valve of the general 45 character hereinafter more fully set forth; and, the invention consists, furthermore, in the novel arrangements and combinations of the several devices and parts, as well as in the details of the construction of the 50 said parts, all of which will be more fully described in the following specification, and then finally embodied in the clauses of the claim which are appended to and which form an essential part of the said specifica- 55 tion.

The invention is clearly illustrated in the accompanying drawings, in which:—

Figure 1 is a longitudinal vertical section of a valve made according to and embodying the principles of the present invention, 60 said view showing the normal initial position of the closing member or gate, and the means for operating the same, when the outlet-side of the valve is completely shut off from the inlet-side of the valve. Fig. 65 2 is a transverse vertical section of the valve, said section being taken on line 2—2 in said Fig. 1, looking in the direction of the arrow *x*, and the upper portion of the valve being partly shown in elevation. Fig. 70 3 is a horizontal section of the valve, said section being taken on line 3—3 in said Fig. 1, looking in a downward direction; Fig. 4 is a similar section of the valve, said section being taken on line 4—4 in said 75 Fig. 1; and Fig. 5 is a detail vertical section, taken on line 5—5 in said Fig. 1. Fig. 6 is a sectional view, similar to that shown in Fig. 1, but illustrating the slightly raised position of the closing member or gate, and 80 the means for operating the same, illustrating the slightly opened relation of the outlet-side of the valve to the inlet-side of the valve. Fig. 7 is a transverse vertical section of the valve, said section being taken 85 on line 7—7 in said Fig. 6, looking in the direction of the arrow *y*, and the upper portion of the valve being partly shown in elevation. Fig. 8 is a horizontal section of the valve, said section being taken on line 90 8—8 in said Fig. 6, looking in a downward direction; Fig. 9 is a similar section of the valve, said section being taken on line 9—9 in said Fig. 6; and Fig. 10 is a detail vertical section, taken on line 10—10 in said 95 Fig. 6. Fig. 11 is a longitudinal vertical section of the valve, showing the position of the closing member or gate, when turned into a plane at right angles to the plane of the closing member or gate represented in 100 said Fig. 1, to provide a completely opened passage between the outlet-side and the inlet-side of the valve; Fig. 12 is a vertical section of the valve, said section being taken on line 12—12 in said Fig. 11; Fig. 13 is a 105 horizontal section of the valve, said section being taken on line 13—13 in said Fig. 11; and Fig. 14 is a similar vertical section, taken on line 14—14 in said Fig. 11.

Similar characters of reference are em- 110

ployed in all of the said above described views, to indicate corresponding parts.

Referring now to the said drawings, the reference-character 1 indicates the complete 5 valve showing one embodiment of the principles of the present invention, the same comprising a suitably-shaped main valve-casing or shell 2, formed at one side with an inlet-element, as 3, which may be formed 10 with the usual flange 4, or other suitable means for the attachment thereto of a pipe, and formed at its opposite side with an outlet-element, as 5, which may be internally screw-threaded, as at 6, or may be provided with other suitable means, for the attachment thereto of another pipe, as will be clearly evident. The said valve-casing or shell 2 is made with a downwardly extending receiving portion, as 7, formed with a 15 seating portion 8, and a pair of socket-like parts 9 and 10, said socket-like parts 9 and 10 being in alinement longitudinally of the valve and being located in the central and longitudinally extending vertical plane of 20 the valve. Resting upon said seating portion 8 is a correspondingly formed disk, as 11, formed with opening, as 12 and 13, respectively, in registration with the socket-like parts 9 and 10. The said receiving portion 7 is also provided with a screw-threaded hole, as 14, into which is screwed the screw-threaded end-portion 16 of a stop-pin or stud, as 15, the shank of the said pin or stud extending through a correspondingly 25 placed hole or perforation 17 in the said disk 11, substantially as shown in Figs. 1, 6 and 9 of the drawings. The said main valve-casing or shell 2 is also made with an upwardly extending chambered member, as 30 18, which is provided at two points, adjacent to the outlet opening of the outlet-element 5, with seats, as 19. Upon its upper outer portion, the said member 18 is provided with a screw-threaded portion 20 upon 35 which is screwed a suitably formed closing cap, as 21, having a centrally disposed bearing-portion 22 for the proper reception and rotation therein of a valve-stem or spindle 23. To prevent any vertical movement of 40 the said stem or spindle, and to at all times maintain the same in its rotatable operative relation, the said member 18 is also formed with an interiorly disposed annular off-set, as 24, which forms a suitable seat for the 45 disposition thereon of a retaining disk or plate 25, said plate 25 being positively held in position upon said off-set 24, by bringing in retaining contact with the marginal edge-portion of said disk or plate 25, the inner 50 annular surface-portion 26 of the above-mentioned closing cap 21, substantially as illustrated in Figs. 1, 6 and 9 of the drawings. The said disk or plate 25 is also provided with a centrally disposed hub, as 27, 55 formed with a central opening which is in-

teriorly screw-threaded, as at 28. Screwed into this screw-threaded opening is an externally screw-threaded nut or collar-like element 29, which is formed with a bearing-portion 30 in which a portion of the shank 70 of the said stem or spindle 23 is rotatably mounted, the said element 29 being also formed with an annular off-set 31, upon which is rotatably seated an annular rib 32 with which the said stem or spindle 23 is provided. The said element 29 is further provided above said off-set 31 with an internally screw-threaded portion 33 into which is screwed another externally screw-threaded nut or collar-like element 34 which 75 is mounted upon the shank-portion of the stem or spindle 23, directly above the said annular rib 32, and when screwed in position thus prevents any vertical movement of the spindle or stem 23, without interfering with the rotating movements of the said spindle or stem, as will be clearly understood from an inspection of said Figs. 1, 6 and 9 of the drawings. The said cap 21 is also provided with an externally screw-threaded projection, upon which is mounted a stuffing-box, as 35, of any usual construction, for packing the stem or spindle 23 at that point, and to provide a tight joint. The lower portion of the shank of the said 80 spindle or stem 23, is screw-threaded, as at 36, and is also provided with a laterally extending stud or projection 37. Upon its upper free end-portion, the said spindle or stem 23 is made with a polygonally-shaped 85 end, as 38, for the reception of a wrench-like handle thereon, by means of which the said stem or spindle may be turned for opening and closing the valve, as will be understood. Other means, however, such as a hand-wheel, or the like, may be employed in connection with the upper end-portion of the said stem or spindle for turning the same, if desired. 90

The reference-character 39 indicates a 95 suitably formed and vertically disposed closing member or gate, in the form of an arc-shaped web, the outer curved surface 40 of which tapers, substantially in the manner shown in Fig. 1 of the drawings, said 100 curved surface, under normal condition, when the valve is closed, registering with and being in contact with the previously-mentioned seats 19 and an arc-shaped seating portion 41 in the inner lower portion of the valve-casing 2, at a point directly below the inner part of the outlet-member 5. Extending horizontally from the upper portion of the said arc-shaped web 39, forming the 105 said closing member or gate, is a member 110 42 formed with an internally screw-threaded hole or opening 43 in alinement with the valve-stem or spindle 23, and into which the screw-threaded portion 36 of the said stem or spindle is 115 120 125 130

screwed, as shown, and whereby the said stem or spindle and the closing member or gate 39 are operatively connected. The said member 42 is also provided with a hole or opening 44 forming a spindle or pin-receiving portion for the purposes to be presently set forth. Similarly extending horizontally from the lower portion of the said arc-shaped web 39, forming the closing member or gate, is another member 45, said member being provided upon its lower surface with a downwardly extending pivot-stud or lug, as 46, which extends into and through the centrally disposed opening 12 of the disk or plate 11, and into the socket-like part 9 of the receiving portion 7, of the main valve-casing or shell 2, substantially as illustrated in the several figures of the drawings. The said member 45, as will be seen from an inspection of Figs. 4, 9 and 13, is cut away, as at 47, and is provided with a pair of horns or stop-projections 48 and 49, adapted to be brought into arresting engagement with the previously-mentioned stop-pin or stud, substantially as shown and for the purposes to be hereinafter more fully described. The said member 45 is also provided with a hole or opening 50, in alignment with the hole or opening 44 in the member 42, and mounted in the said holes or openings 44 and 50 are the respective end-portions of a pin or spindle 51. This pin or spindle 51 has suitably mounted thereon, in a fixed position, a sleeve or collar 52, resting upon the upper surface of the said lower member 45, so that the lower end-portion of the said pin or spindle 51 extends into and through the opening 13 of the disk or plate 11, and into the socket-like part 10 of the receiving portion 7 of the main valve-casing or shell 2, as shown. Encircling that portion of the spindle or pin 51, between the lower surface of said upper member 42 and the said fixed sleeve or collar 52 is a coiled spring 53, the purpose of which is to provide a spring-controlled stop for locking the valve-gate 39 in its closed relation, as will be self-evident, and at one side of the hole or opening 13 in the disk or plate 11, the bounding surface-portion of said disk or plate 11 is inclined or cut away, as at 54, see Fig. 6 of the drawings, and the purpose of which will be presently fully set forth.

Having in the foregoing described the general construction and arrangement of the several devices and parts comprising the valve-ccnstruction, I will now briefly set forth the manner of working the valve and the operaticns of its parts for the purposes stated in the introduction of this specification.

When the several devices and parts of the valve are in the respective positions indicated in Figs. 1 to 5 inclusive, then the arc-shaped web or closing gate 39 completely

shuts off the inlet-side from the outlet-side of the valve. As soon, however, as the spindle or stem 23 receives its initial rctary motion, from right to left, then the screw-threaded portion 36 of said stem or spindle 70 will cause an upward movement of the said arc-shaped web or gate 39 from its closing position shown in Fig. 1 to its vertically raised position indicated in Fig. 6 of the drawings, the lower end-portion of the spindle or pin 51, while still extending into the receiving socket-like part 10, preventing any rctary or swinging action of the said arc-shaped web or closing gate 39, as will be clearly evident. The upward movement of 80 the said web or gate 39, causes it to become unseated from the seat-portions within the main shell or casing 2, so that the pressure within the valve-casing or shell 2 will become equalized upon both sides of the raised 85 web or gate 39. The further rctary motion of the valve-stem or spindle 23, from right to left, brings the lower end-portion of the pin or spindle 51 into the opening 13 in the disk or plate 11, and the end-portion of the 90 pin or spindle 51 will ride up the inclined surface 54, and there being no further opposition to a swinging movement of the pin or spindle 51, about the pivot-stud or lug 46 as a center, the stud or projection 37 of the 95 stem or spindle 23 at the same time having been moved into contact with an extension or post 56 with which the upper member 42 is provided, as clearly shown in Figs. 11 and 12 of the drawings, whereby the active co-operation of the screw-portion 36 with the member 44 being arrested, and the said web or gate 39 is swung around into its entirely 100 opened position indicated in Figs. 11 and 13 of the drawings, thereby providing an 105 unobstructed full passage-way between the inlet-side and the outlet-side of the valve, as will be clearly understood. The previously-mentioned stop-projections or horns 48 and 49 being respectively brought into 110 contact with the stop-pin or stud 15, arrest the said closing web or gate 39 in either its fully opened or fully clsed positions.

In turning the valve-stem or spindle 23 from left to right, the operations are reversed, the spring 53, as soon as the spindle or pin 51 is again moved above the registering openings 13 and 10, causing the lower end-portion of said spindle or pin 51 to be again forced into locked engagement 115 with said openings, so that the closing web or gate 39 is positively retained in its closed relation with the outlet-end of the valve, as will be clearly understood.

Of course I am fully aware that some 120 changes may be made in the general arrangements and combinations of the several devices and parts, as well as in the details of the construction of the said parts, without departing from the scope of the 125 130

present invention as set forth in the foregoing specification, and as defined in the clauses of the claim which are appended to the said specification. Hence, I do not limit the present invention to the exact arrangements and combinations of the several devices and parts as described in the said specification, nor do I confine myself to the exact details of the construction of the said parts as illustrated in the accompanying drawings.

I claim:—

1. A valve comprising a main valve-casing formed with an inlet and an outlet member, a vertically disposed web-shaped and spring-stop controlled closing gate within said valve-casing and normally located in front of said outlet member so as to fully close the same, and means coöperating with said closing gate for primarily raising said gate directly in its position in front of the said outlet member without rotation of said gate and secondarily moving said raised gate horizontally away from in front of said outlet member.

2. A valve comprising a main valve-casing formed with an inlet member and an outlet member, a vertically disposed arc-shaped and spring-stop controlled closing gate within said valve-casing and normally located in front of said outlet member so as to fully close the same, and means co-operating with said closing gate for primarily raising said gate directly in its position in front of the said outlet member without rotation of said gate and secondarily rotating said raised gate horizontally away from in front of said outlet member.

3. A valve comprising a main valve-casing formed with an inlet member and an outlet member, a vertically disposed arc-shaped and spring-stop controlled closing gate within said valve-casing and normally located in front of said outlet member so as to fully close the same, means coöperating with said closing gate for primarily raising said gate directly in its position in front of the said outlet member without rotation of said gate and secondarily rotating said raised gate horizontally away from in front of said outlet member, and a stop-lug within said valve-casing with which the said closing gate is brought into engagement to limit the rotary movement of said gate.

4. A valve comprising a main valve-casing formed with an inlet member and an outlet member, a valve-stem rotatably mounted in said casing, said stem being provided with a screw-threaded portion, a vertically disposed and spring-stop controlled closing gate within said valve-casing and normally located in front of said outlet member so as to fully close the same, and a horizontally disposed member extending from said gate, said member being provided

with a screw-threaded hole with which the screw-threaded portion of said valve-stem coöperates for primarily raising said gate directly in its position in front of said outlet member without rotation of said gate and secondarily rotating said raised gate horizontally away from in front of said outlet member.

5. A valve comprising a main valve-casing formed with an inlet member and an outlet member, a valve-stem rotatably mounted in said casing, said stem being provided with a screw-threaded portion, a vertically disposed and spring-stop controlled closing gate within said valve-casing and normally located in front of said outlet member so as to fully close the same, and a horizontally disposed member extending from said gate, said member being provided with a screw-threaded hole with which the screw-threaded portion of said valve stem coöperates for primarily raising said gate directly in its position in front of said outlet member without rotation of said gate and secondarily rotating said raised gate horizontally away from in front of said outlet member and a stop-lug within said valve-casing with which the said closing gate is brought into engagement to limit the rotary movement of said gate.

6. A valve comprising a main valve-casing formed with an inlet member and an outlet member, a valve-stem rotatably mounted in said casing, said stem being provided with a screw-threaded portion, and a projection extending laterally from the shank of said valve-stem, a vertically disposed and spring-stop controlled closing gate within said valve-casing and normally located in front of said outlet member so as to fully close the same, a horizontally disposed member extending from said gate, said member being provided with a screw-threaded hole with which the screw-threaded portion of said valve-stem coöperates for raising said gate directly in its position in front of said outlet member, and a post extending upwardly from said horizontally disposed member with which the projection of said valve-stem is adapted to be brought into engagement for rotating said raised gate horizontally away from in front of said outlet member.

7. A valve comprising a main valve-casing formed with an inlet member and an outlet member, a valve-stem rotatably mounted in said casing, said stem being provided with a screw-threaded portion, and a projection extending laterally from the shank of said valve-stem, a vertically disposed and spring-stop controlled closing gate within said valve-casing and normally located in front of said outlet member so as to fully close the same, a horizontally disposed member extending from said gate,

said member being provided with a screw-threaded hole with which the screw-threaded portion of said valve-stem coöperates for raising said gate directly in its position in front of said outlet member, a post extending upwardly from said horizontally disposed member with which the projection of said valve-stem is adapted to be brought into engagement for rotating said raised gate horizontally away from in front of said outlet member, and a stop-lug within said valve-casing with which the said closing gate is brought into engagement to limit the rotary movement of said gate.

8. A valve comprising a main valve-casing formed with an inlet member and an outlet member, and with a downwardly extending receiving portion provided with a pair of socket-like parts and a seating portion, a disk seated upon said seating portion, said disk being provided with a pair of openings in registration with said socket-like parts, a valve-stem rotatably mounted in said valve-casing, said stem being provided with a screw-threaded portion, a vertically disposed closing gate within said valve-casing normally located in front of said outlet member so as to fully close the same, an upper horizontally disposed member extending from said gate, said member being provided with a screw-threaded hole with which the screw-threaded portion of said valve-stem coöperates for primarily raising said gate directly in its position in front of said outlet member and secondarily rotating said raised gate from in front of said outlet member, a lower horizontally disposed member extending from said gate, a pivot-stud extending downwardly from said lower horizontally disposed member, said pivot-stud extending through one of the openings in said disk and into one of the socket-like portions in the downwardly extending receiving portion of the valve-casing, said upper horizontally disposed member being provided with an opening, said opening being in alinement with the other opening in said disk and the other socket-like portion in the downwardly extending receiving portion of the valve-casing, said upper horizontally disposed member being provided with an opening, said opening being in alinement with the other opening in said disk and the other socket-like portion in the downwardly extending receiving portion of the valve-casing, and a spring-controlled lock-pin slidably mounted in said alined last-mentioned openings and the said last-mentioned socket-like portion, and a stop-lug connected with said downwardly extending receiving portion of the valve-casing with which portions of the lower horizontally disposed member is adapted to be brought into engagement to limit the rotary movement of said gate.

10. A valve comprising a main valve-casing formed with an inlet member and an outlet member, and with a downwardly extending receiving portion provided with a pair of socket-like parts and a seating portion, a disk seated upon said seating portion, said disk being provided with a pair of openings in registration with said socket-like parts, a valve-stem rotatably mounted in said valve-casing, said stem being provided with a screw-threaded portion, and a projection extending laterally from said valve-stem, a vertically disposed closing gate within said valve-casing normally located in front of said outlet member so as to fully close the same, an upper horizontally disposed member extending from said gate, said member being provided with a screw-threaded hole with which the screw-threaded portion of said valve-stem coöperates for primarily raising said gate directly in its position in front of said outlet member, and a post extending upwardly from said horizontally disposed member with which the projection of said valve-stem is adapted to be brought into engagement for rotating said raised gate away from in front of said outlet member, a lower horizontally disposed member extending from said gate, a pivot-stud extending downwardly from said lower horizontally disposed member.

9. A valve comprising a main valve-casing formed with an inlet member and an outlet member, and with a downwardly extending receiving portion provided with a pair of socket-like parts and a seating portion, a disk seated upon said seating portion, said disk being provided with a pair of openings in registration with said socket-like parts, a valve-stem rotatably mounted in said valve-casing, said stem being provided with a screw-threaded portion, a vertically disposed closing gate within said valve-casing normally located in front of said outlet member so as to fully close the same, an upper horizontally disposed member extending from said gate, said member being provided with a screw-threaded hole with which the screw-threaded portion of said valve-stem coöperates for primarily raising said gate directly in its position in front of said outlet member, and a post extending upwardly from said horizontally disposed member with which the projection of said valve-stem is adapted to be brought into engagement for rotating said raised gate away from in front of said outlet member, a lower horizontally disposed member extending from said gate, a pivot-stud extending downwardly from said lower horizontally disposed member.

- izontally disposed member, said pivot-stud extending through one of the openings in said disk and into one of the socket-like portions in the downwardly extending receiving portion of the valve-casing, said upper horizontally disposed member being provided with an opening, said opening being in alinement with the other opening in said disk and the other socket-like portion 10 in the downwardly extending receiving portion of the valve-casing, and a spring-controlled lock-pin slidably mounted in said alined last-mentioned openings and the said last-mentioned socket-like portion.
- 15 11. A valve comprising a main valve-casing formed with an inlet member and an outlet member, and with a downwardly extending receiving portion provided with a pair of socket-like parts and a seating portion, a disk seated upon said seating portion, said disk being provided with a pair of openings in registration with said socket-like parts, a valve-stem rotatably mounted in said valve-casing, said stem being provided with a screw-threaded portion, and a projection extending laterally from said valve stem, a vertically disposed closing gate within said valve-casing normally located in front of said outlet member so as to 25 fully close the same, an upper horizontally disposed member extending from said gate, said member being provided with a screw-threaded hole with which the screw-threaded portion of said valve-stem cooperates for primarily raising said gate directly in its position in front of said outlet 30 member, and a post extending upwardly from said horizontally disposed member with which the projection of said valve-stem is adapted to be brought into engagement for rotating said raised gate away from in front of said outlet member, a lower horizontally disposed member extending from said gate, a pivot-stud extending downwardly from said lower horizontally disposed member, said pivot-stud extending through one of the openings in said disk and into one of the socket-like portions in the downwardly extending receiving portion of the valve-casing, said upper horizontally disposed member being provided with an opening, said opening being in alinement with the other opening in said disk and the other socket-like portion in the downwardly extending receiving portion of the valve-casing, a spring-controlled lock-pin slidably mounted in said alined last-mentioned openings and the said last-mentioned socket-like portion, and a stop-lug connected with said downwardly extending receiving portion of the valve-casing with which portions of the lower horizontally disposed member is adapted to be brought into engagement to limit the rotary movement of said gate. 35
- In testimony, that I claim the invention set forth above I have hereunto set my hand this 14th day of April, 1915.
- HALFDAN NORBOM.
